ELASTIC CLASP PAD AND METHOD OF PRODUCING THE SAME

Filed Aug. 28, 1933

UNITED STATES PATENT OFFICE

2,093,623

ELASTIC CLASP PAD AND METHOD OF PRODUCING THE SAME

Allen D. Strahm, Tulsa, Okla., assignor to Snap-pies, Inc., Tulsa, Okla., a corporation of Oklahoma

Application August 28, 1933, Serial No. 687,142

2 Claims. (Cl. 24—248)

This invention relates to new and useful improvements in elastic clasp pads.

One object of the invention is to provide an improved pad having a metallic base or supporting plate and an elastic member molded thereon provided with a gripping face, whereby the pad may be securely fastened in place in the clasp with only its gripping face exposed to grip an article, and also whereby the elastic member of the pad is held in shape when carrying out its gripping action.

An important object of the invention is to provide a pad having an elastic gripping member so firmly fastened to a metallic base plate as to resist creeping or buckling when subjected to lateral thrusts.

Still another object of the invention is to provide an elastic pad which will be self-supporting and which will possess sufficient inherent rigidity to grip and hold an article when overhanging its support.

A construction designed to carry out the invention will be hereinafter described, together with other features of the invention.

The invention will be more readily understood from a reading of the following specification and by reference to the accompanying drawing in which an example of the invention is shown, and wherein:

30 Figure 1 is a perspective view of a metallic blank including a plurality of base plates constructed in accordance with the invention,

Figure 2 is a perspective view showing a strip of completed pads prior to cutting from the strip,

35 Figure 3 shows the same pads cut from the strip,

Figure 4 shows two of the pads separated and ready for mounting in a clasp,

Figure 5 is an enlarged transverse sectional view taken on the line 5—5 of Figure 3,

Figure 6 is a perspective view of a base plate for forming a companion pad to that shown in Figures 3 and 4,

Figure 7 shows the elastic material applied to 45 the metal base plate,

Figure 8 is a perspective of a strip from which a pad has been punched,

Figure 9 is a perspective view of one of the pads punched from the strip, and

50 Figure 10 is a perspective view of a clasp equipped with pads constructed in accordance with the invention.

In the drawing the numeral 10 (Figures 1 to 5) designates a metal base plate, of which a number 55 are shown. Each plate is substantially rectangu-

lar and provided with rounded corners 11. The plates are connected by short metallic shanks 12, so that a plurality may be punched or stamped from a sheet or strip of metal. Any suitable metal may be used, but it is necessary to use only such metals as rubber will adhere to. Thin sheets of brass have been found satisfactory for the purpose.

The row or group of metal plates shown in Figure 1 are molded in a strip of rubber 13, as shown in Figure 2, whereby the plates are entirely enveloped. The process whereby the rubber is caused to adhere to the plates is not a part of this invention, but it is essential that the metal and the rubber be united so that the rubber will not 15 creep or buckle on the plate when subjected to lateral or horizontal thrusts. To assist in uniting the plate and the elastic member, perforations 14 may be made in the plate to permit the rubber to flow through and form ties, as is shown 20 in Figures 1 to 5.

In forming the pad, an elastic gripping member 15 is molded on and around the plate and is considerably thicker than the strip 13. The upper surface or face of each pad member 15 is formed 25 with corrugations 16 so as to be recessed. The particular shape is not essential as any form of recesses may be used. However, the corrugations are very effective, as will be hereinafter explained. An aperture 17 is provided in the 30 center of each pad and this extends through the center of each plate 10.

After the pads have been molded as shown in Figure 2, a row is cut out of the strip, as is shown in Figure 3. It is pointed out that any number of parallel rows may be molded in a single sheet of rubber and then cut out in rows. The pads are still connected by the rubber covered shanks 12 when cut out and by breaking off these shanks 40 the pads are separated. Two of the perforations of the plates may be located to weaken the connection between the plates and the shanks, thus making it easier to break off the pads.

In Figures 6 to 9, inclusive, I have shown a 45 companion structure including a metallic base sheet 18 on one side of which is molded a sheet of rubber 19 formed with corrugations 20. In Figures 1 to 5, both sides of the metal are covered with rubber; while in Figures 6 to 9, only one side is so covered. The molded sheet is cut into strips 13' similar to strip 13. Individual pads (Figure 9) are cut from the strip (Figure 8). Each pad includes a base plate 10', a rubber pad member 15' and lugs 21. The pad member has 50 corrugations 16'.

For the purpose of designation, the pad shown in Figures 1 to 5 may be termed the "front" pad F, and that shown in Figures 6 to 9, the "back" pad B. The corrugations 16' of the back pad are made complementary to the corrugations 16 of the front pad, so that when the gripping faces of these two pads are brought together the ridges of one pad will engage in the valleys of the other pad, thereby effecting an undulating gripping of fabrics and the like.

In Figure 10, I have shown the back pad B fastened to the back jaw 25 of a clasp by the lugs 21 which are engaged in said jaw and upset. The front pad F is secured to a narrow front jaw 15 30 by a rivet 31 and overhangs the same. The metal base plate in the pad F gives it sustaining rigidity so that it will hold its gripping relation when the jaws are closed. By extending the corrugations 16 and 16' transversely of the clasp, 20 an article suspended therefrom will be most efficiently gripped. The rubber being united to the metal plates will not creep or roll up when subjected to lateral thrusts and this is very important.

25 While I have shown the two forms of pads with recessed faces formed by the corrugations 16 and 20, it is to be understood that such corrugations are not essential to the invention and the pad might be produced without recesses.

30 The description which has been given recites more or less detail of a particular embodiment of the invention, which is set forth as new and useful; however, I desire it understood that the invention is not limited to such exact details of construction, because it is manifest that changes

and modifications may be made within the scope of the appended claims without departing from the spirit of the invention.

What I claim and desire to secure by Letters Patent, is:

1. An elastic pad clasp comprising, a pair of cooperating clamping members, a pad comprising a body plate having lug portions at its opposite ends bent into engagement with one of said clamping members, said body plate having a covering of rubber, and the other clamping member having a pad comprising a body plate riveted thereto, said second mentioned body plate having a covering of rubber, the meeting face portions of said pads being corrugated to interfit 10 in clamping relation.

2. A clasp of the character described, comprising, a pair of cooperatively connected rigid clamping members, a separate pad element secured on the free end portion of one of said clamping members, said pad element comprising a flat non-flanged rectangular rigid metal plate having rounded corners and provided with a rubber coating throughout its exposed surface area from margin to margin, the top face portion of the rubber coating being roundingly corrugated, and a complementary pad element on the free end portion of the other clamping member, likewise comprising a similar flat rigid metal plate having rounded corners and a rubber coating, the co- 20 operating face portion of which is roundingly corrugated to interfit the corrugations of said first described pad element.

ALLEN D. STRAHM.
